BRASSIERE
Sydne Cousins, Westport, Conn.
(345 W. 58th St., New York 19, N.Y.)
Filed Feb. 18, 1960, Ser. No. 9,526
3 Claims. (Cl. 128—484)

The invention relates to an undergarment, and more particularly to a brassiere having improved means for supporting the cups thereof upon the body of a wearer, adapted to function independently of such cups.

The primary and fundamental purpose of a brassiere is to furnish control and support to the breasts. Cups are provided in a brassiere to encase the breasts and in order to sufficiently retain the garment in position upon the body, it is necessary to further provide body-encircling bands. One end of such pair of bands is generally secured to the cups along the side edges thereof and the opposite ends are provided with securing means enabling such bands to be joined at the back of the wearer to complete a body encircling structure. It will be evident that such structure, encompassing the bust of the wearer, is completely responsive to any movements affecting the thoracic region of the body, as for example, the expansion and contraction of such area caused by breathing, bending, etc. Any pressure or movement, therefore, exerted upon the body-encircling bands, is directly transmitted to the bust cups and consequently to the breasts encased therein.

In order to control the transmission of such pressure or movement, so that the breasts may remain relatively free of any bodily disturbances, varying attempts have been made to substitute an extremely narrow elastic band to encircle the body. It has been found, however, that continued use of such narrow band tends to crease and dig into the flesh of the underarm area, considered, incidentally, to be generally one of the most fleshy regions of the body.

It is therefore the object of the present invention to provide a brassiere which will furnish control and support to the breasts of a wearer without being affected by bodily movements caused by breathing, bending, or the like.

Another object of the present invention is to provide a brassiere having bust cups functionally independent from the body-encircling structure which retains such cups upon the body of a wearer.

A further object of the present invention is the provision of a brassiere which will furnish adequate support and control to the breasts, and in addition, will adequately confine the fleshy area generally in the underarm region of the body.

Another object of this invention is the provision, in a brassiere, of body encircling portions which will furnish support and control to the fleshy underarm region, and which are additionally adapted to independently support the bust cups in a fixed position and which are self-adjusting upon the body of a wearer.

In accomplishing the foregoing, there is provided, in a brassiere, a body-encircling structure comprising body-encircling bands generally of narrow elastic strips, secured to the outer edges of a pair of bust cups and adapted to be secured at the ends thereof. A generally triangular fabric side portion is provided, such portion being secured to the outer edges of said bust cups at selected points and generally overlapping the outer side edge of each of said bust cups. Such side portion is secured to the narrow elastic strips to furnish control and support to the fleshy underarm region of the body as well as to allow independent action of the cups of the brassiere in response to movement of any kind.

2

Provision is further made for the adjustment and/or partial removal of the side portion so as to allow utilization of the brassiere in conformity with fashion trends of the moment. In addition, the brassiere of the present invention is provided with removable shoulder straps so that it may be utilized as a strapless brassiere when the wearer so desires.

These and other objects and advantages of the present invention will be apparent to those versed in the art, from the following description of a particular embodiment of the invention as illustrated in the drawing wherein like characters designate like parts in the several views and in which:

FIG. 1 is a perspective view of a brassiere constructed according to the present invention, shown in position upon a wearer;

FIG. 2 is a plan view of a portion of the brassiere seen from the rear;

FIG. 3 is a view taken on line 3—3 of FIG. 2;

FIG. 4 illustrates an embodiment of the present invention with the shoulder straps removed, and side portions partially removed and

FIG. 5 is a view of a strapless brassiere according to the present invention.

Referring now to the drawing there is illustrated a brassiere 10 comprising a pair of bust cups 11, 12 formed of a suitable fabric and supported by a rigid or partially rigid reinforcing or stiffening member 13 extending substantially around the periphery of said cups 11, 12 generally in the lower part thereof. Such reinforcing or stiffening member 13 may be of nylon, Dureen, or other plastic material, or if desired, a metal wire may be used.

A medial portion 14, generally of non-stretchable fabric is provided between said bust cups 11, 12 serving to separate said cups.

A body-encircling structure comprising a triangular side portion 20 presently to be described, and a pair of narrow elastic body bands 15 are provided. Such bands 15 are secured by stitching at one end thereof to the outer edge of said bust cups 11, 12 generally in the lower region thereof, and are provided with fastening means, not shown, at their other ends, so that when the ends of said bands 15 are secured, brassiere 10, will encircle the body and be retained in a desired position upon the body of a wearer.

Since both cups 11, 12 are substantially identical, reference will be made to one such cup in the description of the invention using bust cup 11 as illustrative thereof.

The brassiere 10 is provided with an inverted V tab member 16, one arm 17 of which is secured by stitching to the top edge of bust cup 11 and the remaining arm 18 of said V shaped tab member 16 is attached to a substantially triangular side portion 20 of the body encircling structure. Shoulder strap 19 is adjustably secured at one end to said inverted V tab member 16 at the apex thereof, and the other end of said shoulder strap 19 is secured to body encircling elastic band 15.

As heretofore mentioned, the body encircling structure is further comprised of a generally triangular side portion 20. One corner 21 of said side portion is secured by stitching to arm 18 of said inverted V tab 16. A second corner 22 of side portion 20 is secured to cup 11 of the brassiere preferably at a medial point along the lower edge thereof and a third corner 23 of side portion 20 is secured by stitching to body encircling band 15. It is especially to be noted that the attachment of corner 23 to elastic band 15 is such that said side portion 20 remains in a flaccid condition when elastic band 15 is distended. Edge 24 between corner 21 and 22 is generally arcuate, conforming to, and overlapping the outer side edge of bust

When the garment is placed upon the body of a wearer, elastic body band 15 is extended causing triangular side portion 20 to be drawn taut, side portion 20 thus assuming its confining and supporting function of the fleshy underarm region. The arcuate edge 24, being laterally drawn by said elastic bands 15, assumes a position along the side edge of bust cup 11 without in any way substantially affecting or exerting a pulling force on bust cup 11. As side portion 20 is drawn taut, the pulling force exerted upon corner 21 is related directly to arm 18 of inverted V tab 16, so that such pulling force upon shoulder straps 19 is avoided and digging of such shoulder straps 19 into the fleshy shoulder area of the body is avoided.

Where a brassiere 10 of the character described is provided with a medial portion 50 between bust cups 11, 12 which extends below said bust cups 11, 12 to a mid point along the bottom edge thereof, as illustrated in FIG. 5, an elastic tab 51 is provided, connecting the edge of said medial portion at its terminal below the bust cup, and corner 22 of said side portion 20.

The brassiere 10 may likewise be adapted as a strapless garment, as illustrated in FIG. 5, in which case, corner 21 of side portion 20 is secured by stitching to a point medially the upper edge of said bust cup 11.

The brassiere 10 of the present invention may further be modified to allow removability of the shoulder straps by providing securing means allowing for the removal and/or replacement of inverted V tab and removal of corner 21 therefrom. In the aforementioned case, upon the removal of corner 21 from bust cup 11, such corner may be concealed behind elastic band 15, thus converting said brassiere to a strapless garment.

Attachment of corner 23 to elastic band 15 may be by the use of adjustable securing means whereby relative 35 flaccid adjustment of the triangular side portion 20 may be achieved to suit the particular desires of a wearer.

The brassiere 10, as thus described, may be worn with straps or may be worn as a strapless garment but in any case, once elastic bands are extended, causing side portion 20 to become taut against the fleshy underarm area of the body, the pulling force created by the elastic bands 15 is transmitted to the shoulder straps 19 and the elastic tab 51 forming part of the medial portion of the brassiere, leaving bust cups 11 completely free of such pull. Likewise, 45 where the one corner 22 is directly secured to the bust cup 11, as illustrated in FIG. 2, and FIG. 4, such pulling force is greatly reduced since no attachment obtains along the entire side edge of cup 11 as is normally the case in the standard garment.

It is to be understood that the present invention is not limited to embodiments described and illustrated in the drawing, but various embodiments and adaptations may be made without departing from the spirit and scope of the present invention as herein described and defined.

It is further to be understood that the present invention may be used in bust sections, as for example, in swim suits, corselets, halters, and slips.

I claim:

1. A bust-encircling garment comprising:
  - (a) a pair of bust cups;
  - (b) means separating said bust cups;
  - (c) body-encircling bands secured to the outer edges of each of said bust cups;
  - (d) a substantially three-cornered triangular side portion partially overlaying each of said body-encircling bands and said bust cups along the outer perimeter thereof;

4

(e) said side portions, at one corner thereof, being detachably secured to said bust cups medially at the top edge thereof;

(f) a second corner of said side portions being secured to said bust cups at a point medially along the bottom edge thereof; and

(g) a third corner of said side portions being secured to said body-encircling bands at a point outwardly from the outer edge of said bust cups.

2. A bust-encircling garment comprising:

- (a) a pair of bust cups;
- (b) means separating said bust cups;
- (c) body-encircling bands secured to the outer edges of each of said bust cups;
- (d) a substantially three-cornered triangular side portion partially overlaying each of said body-encircling bands and said bust cups along the outer perimeter thereof;

(e) a pair of substantially V-shaped tabs;

(f) one arm of said tabs being secured to said bust cups at a point medially of the upper edge thereof;

(g) the other arm of said tabs being detachably secured to one corner of said side portions;

(h) a second corner of said side portions being secured to said bust cups at a point medially along the bottom edge thereof;

(i) a third corner of said side portions being secured to said body-encircling bands at a point outwardly from the outer edges of said bust cups;

(j) shoulder straps, one end of which is secured to said V tabs at the apex thereof; and

(k) said shoulder straps at the other end thereof being secured to said body-encircling bands at the rear thereof.

3. A bust-encircling garment comprising:

- (a) a pair of bust cups;
- (b) means separating said bust cups;
- (c) body-encircling bands secured to the outer edges of each of said bust cups;
- (d) shoulder straps secured at one end thereof to said bust cups medially at a point along the upper edge thereof;

(e) the other end of said shoulder straps being secured to said body-encircling bands at the rear thereof;

(f) a substantially three-cornered triangular side portion partially overlaying each of said body-encircling bands and said bust cups along the outer perimeter thereof;

(g) said side portions, at one corner thereof, being detachably secured to said shoulder straps at a point above the upper edge of said bust cups;

(h) a second corner of said side portions being secured to said bust cups at a point medially along the bottom edge thereof; and

(i) a third corner of said side portions being secured to said body-encircling bands at a point outwardly from the outer edge of said bust cups.
